UNITED STATES PATENT OFFICE.

FRANK THORNTON, JR., OF PITTSBURGH, PENNSYLVANIA, ASSIGNED TO WESTINGHOUSE ELECTRIC AND MANUFACTURING COMPANY, A CORPORATION OF PENNSYLVANIA.

TERMINAL CONNECTOR FOR CURLING-IRONS AND THE LIKE.

1,173,621.

Specification of Letters Patent. Patented Feb. 29, 1916.

Application filed May 1, 1913. Serial No. 764,818.

To all whom it may concern:

Be it known that I, FRANK THORNTON, Jr., a citizen of the United States, and a resident of Pittsburgh, in the county of 5 Allegheny and State of Pennsylvania, have invented a new and useful Improvement in Terminal Connectors for Curling-irons and the like, of which the following is a specification.

10 My invention relates to electrically heated apparatus, and it has special reference to terminal plug connectors for curling irons and the like.

The object of my invention is to provide 15 curling irons and other electrical apparatus with a simple, inexpensive and detachable terminal connector.

Heretofore, it has not been the usual practice to provide curling irons with detachable 20 plug connectors and, consequently, more or less inconvenience has resulted. In former designs also, the movable tong was permanently fastened upon the iron, which has been found to be an undesirable feature in 25 many cases.

According to my present invention, I provide a detachable plug-connector which is adapted for insertion within the handle of the iron and which, in addition, has a self- 30 clamping feature.

Also, I provide a readily detachable spring-supported tong.

In the accompanying drawing, Figure 1 is a longitudinal section of a curling iron 35 constructed in accordance with my invention; Fig. 2 is a view, in elevation, with parts broken away, taken at right angles to Fig. 1; Fig. 3 is a sectional view, taken on line III—III of Fig. 1; Fig. 4 is a sectional view, on line IV—IV of Fig. 2, and Fig. 5 is a sectional view on line V—V of Fig. 4.

Referring to the drawing, a curling iron 1 comprises a removable heater 2, an incasing member 3 therefor, a detachable tong 4, a 40 tubular handle 5, and a plug connector 6 disposed within the handle.

The removable heater 2 comprises a central rod 7, an insulating cement sheath 8 and a helically wound conductor 9 embedded 45 in the sheath. One end of the heating element 9 is connected to the outer end of the rod 7 and its other end is connected to a shell 10 that is insulated from, and concentrically disposed around said rod near its

inner end. The space between the heater 55 and the incasing shell 3 may be filled with cement or other suitable material.

The outer end 11 of the incasing member 3 is closed, and its other end is expanded to constitute a ferrule 12 into which the handle 60 5 is screwed or otherwise fastened.

The ferrule is provided with a plurality of oppositely disposed pins 13 for use in connection with the tong 4, as hereinafter described.

The tong 4 comprises an approximately 65 semi-cylindrical cap 14 that fits over the incasing shell 3 and is pivotally mounted on the pins 13 of the ferrule 12, and an outwardly projecting lever 15 for moving the 70 cap away from the shell 3. The tong 4 is biased to its closed position by a spring 16 one end of which is attached to the lever 15 and the other end of which bears against the ferrule 12 intermediate the pins 13; the 75 tong is detachably mounted on the pins 13 by means of a pair of longitudinally extending hooks 17. Though normally held in position by the spring 16, the tong 4 may readily be detached, as will be seen from the 80 foregoing description.

The handle 5 may be of any convenient 85 form, and is made hollow for the reception of the lower end of the heater 2 and the plug-connector 6. As a means of connecting the heater terminals 7 and 10 to the supply circuit through the connector 6, a plurality of stationary terminal strips 18, that are adapted for insertion in the connector, 90 are partially embedded in a block 19 of suitable insulating material that is disposed within the handle 5 beyond the end of the heater 2. A plurality of suitably formed 95 spring fingers 20 and 21, that are severally adapted to make resilient contact with the heater terminals 7 and 10, are riveted, or otherwise suitably connected, to the stationary terminal strips 18. The heater 2 is thereby allowed a certain amount of free movement and is less liable to breakage.

The plug-connector 6 comprises a suitably 100 chambered split socket 22 of insulating material, and a plurality of switch jaw members 23 that are severally connected to supply conductors 24, and suitably held within 105 said socket.

The connector 6 is disposed within the handle 5, and the jaws 23 are adapted to en-

gage the stationary terminals 18, as hereinbefore stated. One member 25 of each of the jaws 23 is immovably attached to the socket 22 and the other member 26 is movable laterally to a limited degree. Each of the members 25 is provided with a pair of oppositely-disposed ears 27 that are bent at right angles to its body portion and have centrally disposed openings 28. The movable members 26 are provided with oppositely-disposed lugs 29 that project through the openings 28 in the ears 27. A pair of oppositely-disposed pins 30 are slidably disposed in openings in the socket 22 in position to engage the outer faces of the jaw members 26, and a pair of springs 31 that are attached to a supporting band 32 upon the outer end of the socket, act upon the pins to resiliently hold the movable jaw members 26 in engagement with the respective stationary terminals 18.

Assuming the connector 5 to be in the position shown in Fig. 1, the operation of the switch parts when the plug is removed, is as follows: The jaws 23 are disengaged from the stationary terminals 18 against the action of the spring-supported pins 30, which tend to close them. In inserting the connector, the jaws 23 are forced over the terminals 18 against the action of the spring-actuated pins, any necessary movement of the jaw members 26 being permitted by movement of the lugs 29 within the openings 28 in the ears 27. A constant pressure is thus imposed on the switch jaws to maintain the circuit connections.

I do not wish to be restricted to the specific structures and details herein set forth, but desire that only such limitations shall be imposed as are indicated in the appended claims.

I claim as my invention:

1. A switching device embodying coöperating stationary and movable contact mem-

bers and additional automatic and resili- 45
ently actuated means for clamping said contact members in position.

2. A switching device embodying coöperating stationary and movable contact members, and automatic resiliently actuated 50
means disposed at right angles to their plane of contact for clamping said contact members in position.

3. A switching device embodying coöperating stationary and movable contact members, an insulating casing therefor, a plurality of resilient members attached to said casing, and a plurality of movable members associated with said resilient members for clamping said contact members in position. 55

4. A switching device embodying coöperating stationary and movable contact members, an insulating casing therefor, a plurality of resilient members attached to said casing and a plurality of movable pins actuated by said resilient members for clamping 60
said contact members in position. 65

5. A switching device embodying a plurality of stationary contact members, a plurality of coöperating movable contact members each provided with an additional 70
loosely attached contact member, an insulating casing for said contact members provided with a plurality of transverse openings, a plurality of flat springs attached to 75
said casing, and a plurality of pins disposed at right angles to the plane of contact and adapted to move through said openings and actuated by said springs for clamping 80
said loosely attached contact members against said other contact members.

In testimony whereof, I have hereunto subscribed my name this 24th day of April 1913.

FRANK THORNTON, JR.
